Edward Halsey.

UNITED STATES PATENT OFFICE.

EDWARD HALSEY, OF SAN JOSÉ, CALIFORNIA, ASSIGNOR OF ONE-HALF
TO HARRY BARLING, OF SAME PLACE.

TURN-TABLE.

SPECIFICATION forming part of Letters Patent No. 248,311, dated October 18, 1881.

Application filed June 10, 1881. (No model.)

To all whom it may concern:

Be it known that I, EDWARD HALSEY, of the city of San José, county of Santa Clara, State of California, have invented certain new and useful Improvements in Turn-Tables for Railroads and Draw-Bridges, and for other purposes, of which the following is a specification.

The nature and object of my invention is the novel construction of a turn-table, in which the friction is reduced to its minimum, as will be more fully shown by reference to the accompanying drawings, in which—

Figure 1 shows the top plate inverted, with the friction-rollers and carriage in the proper position. Fig. 2 is an elevation of the turn-table. Fig. 3 is a sectional view of the same.

A is the bottom plate or circular track on which the face of the friction-roller *a* runs. The friction-roller is slightly convexed on its face to allow the axles to properly operate upon the circular tracks of the top plate.

B is the top plate, which is grooved, as shown at *b*, sufficiently to allow the rollers *a* to revolve therein without coming in contact with the sides of the groove thus formed. This groove forms on the top plate a circular track on each side of the friction-roller, as shown at *c* and *d*. The circular tracks rest upon and are supported on the axles of the friction-rollers *a*. The axles *e* of the friction-rollers are of such conical shape, the larger end of

the cone revolving on the outer track, *c*, of the top plate, and the smaller end revolving on the inner track, *d*, that each end travels on its corresponding plane or track in a perfect circle without abrasion.

The friction-rollers *a* are kept in proper position by two circles, *f* and *g*, in which they are pivoted, as shown at *h*, at proper distance from each other, and which is denominated a "carriage," and which revolves around the common center as the rollers are moved. These circles are braced at proper distance to be always kept parallel to each other.

j is the center pin or bolt on which the table turns, and *k* is the corresponding socket therefor. Any movement of the table causes the friction-rollers *a* to revolve on the bottom plate or track, and at the same time the axles *e* revolve in the same direction upon the tracks *c* and *d* of the top plate, thus dispensing with all journal friction.

I claim as my invention—

The combination of the track A, friction-rollers *a*, the groove *b*, the circular tracks *c* and *d*, the conical axles *e*, and the carriage *f* *g*, substantially as and for the purposes hereinbefore set forth.

EDWARD HALSEY.
